GEORGE B. WALLACE, OF GRANTWOOD, NEW JERSEY, ASSIGNOR TO THE AMERICAN LAUNDRY MACHINERY COMPANY, OF CINCINNATI, OHIO, A CORPORATION OF OHIO

LOADING APPARATUS FOR LAUNDRY WASHERS AND THE LIKE

Application filed February 18, 1931. Serial No. 516,605.

The invention disclosed in this application relates to load maintaining and feeding mechanism for fabric treating machines such as washers, dry cleaners, tumblers and the like wherein there is a revolving cylinder provided with a plurality of radially disposed pockets each adapted to receive a definite predetermined load, lot, batch, or charge.

In treating laundry work and the like, in order to maintain the proper segregation of loads, lots or batches of laundry, it is necessary that these different units after being metered out be charged intact into the treating machine without danger of there being mixing of one unit with another or without losing a single article. The necessity for such handling of laundry work is that the particular laundry of each customer, for example, must be kept separate from that of another customer, or where individual identification is used it is necessary to maintain predetermined lots or batches intact throughout the various laundry treatments so that any instrumentality, no matter how simple, or how seemingly obvious which tends to maintain or assist in perpetuating the predetermined separation of the lot, batch or load is of the greatest importance.

In the average laundry there are a number of different treatments to which the work must be subjected and in almost every instance it is practically compulsory that all the washing and like machines be arranged close together to avoid expensive piping and to segregate this more or less sloppy process from other treatments. In such a situation, therefore, available space for trucks loaded with the different lots, batches or loads is very limited and many times results in disturbing the classification which might otherwise remain intact.

The present invention aims to overcome the difficulties inherent in fabric treating installations such as laundries by providing the washing or fabric treating machines with means for maintaining and feeding the proper loads to the fabric cylinder whether this cylinder contains only one annular group of pockets or a plurality of groups of such pockets arranged side by side throughout the

length of the cylinder. In the special arrangement shown, the feeding device is in the form of a chute provided with a plurality of doors similar to trap doors separating the chute into a plurality of load receiving maintaining and feeding hoppers delivering their load successively one into the other and from the lower-most one into the treating machine pocket. But these devices have never been controlled in their operation by an operator operated control which would by successive operator operated operations transfer the batches one after the other from hopper to hopper and into the washer and it is this arrangement which forms the subject matter of this application.

Other details of construction and operation will be clearly set forth in the following description, drawings, and claims.

In the embodiment of the invention shown in the drawings, Fig. 1 shows a fabric treating machine of the multiple Y pocket type with plural group pocket arrangement together with a feeding chute extending through to the floor above where the load metering takes place; Fig. 2 is a vertical sectional view of a section of the chute with parts broken away; Fig. 3 is a similar view looking from right to left in Fig. 2; Fig. 4 is a vertical section looking at the right hand end as shown in Fig. 1; Fig. 5 is a detailed view of the cam mechanism for stepping the control bar around for the successive release of the trap doors; Fig. 6 is a section upon the line 6-6, Fig. 5; Fig. 7 is a view similar to Fig. 4 showing a modified form; and Fig. 8 is a section upon the line 8-8 of Fig. 7.

In the drawings, 1 represents the outer casing of a washing or like machine adapted to receive the treating liquid or medium. Within this casing is a revolving casing 2 provided with a plurality of Y pockets 3, 4 and 5 there being three shown in the drawings. These pockets 3, 4 and 5 are radially extending pockets arranged in an annular group. In addition to this group of pockets, there is shown another group similar in all particulars and built into the same cylinder. It is common practice to provide each of these pockets with a door 6 which opens and

closes the opening into each pocket and it is also common practice to provide the casing 1 with a suitable opening indicated at 7 and arranged to be closed by an outer door 5 generally indicated at 8. The annular arrangement of the pockets also produces a longitudinal group of like pockets as shown and when a longitudinal group of pockets are in proper position access may be had to them through the casing and through the pocket door. The foregoing describes in a more or less cursory way the usual type of Y pocket washing machine and the present invention is particularly adaptable to such a 10 machine.

Supported above the washing, or other like machine, is the feeding mechanism comprising the lower delivery chute portion comprising the two longitudinal chute parts 9 20 each having its mouth in a position to align with a pocket. In the instance shown, there are two annular groups of pockets so that the feeding device will have two chute portions and a description of one chute portion 25 will suffice for both except in so far as the control mechanism is common to both and requires further specific description. Standing above the chute part is a main chute body comprising front and end walls 10 the back 30 11 being open and the top being closed by an upper inclined wall 12. Arranged within this main chute body are door portions 13 extending from the opening 11 downwardly and forwardly toward the front as shown in 35 Fig. 4. They only extend for a part of the distance from the front to back as shown to their pivots. These three door portions are preferably arranged above the building floor 14 above the treating machine so that proper 40 loading and charging may take place out of the treating room and in what is normally termed the classifying room. Extending beneath each of these door portions 13 is a door shaft 15. Each of these shafts extends 45 out at the ends of the main chute body where, at one end, it is provided with a counterweight 16 so arranged that the shaft tends to rotate in a counter-clockwise direction as shown in Fig. 2 or as will appear in a door 50 closing direction. Forming a continuation of each door portion 13 is a door portion 17 extending to a point near the wall 10 where it is provided with a latch tongue 18 extending out through an opening 19 in the front 55 wall 10. Mounted on the wall 10 at each opening is a suitable latch plate 20 provided with bearings 21 for a latch shaft 22 which extends along outside the wall 10 and is common to all the doors in the same horizontal 60 plane. This latch shaft at each door is provided with a latch 23 for engaging with the corresponding latch tongue of the corresponding door and serves to hold the door closed against the tendency of the load above 65 the same tending to open it. At the end of

the main chute body shaft 22 is provided a latch operating lever 24 and it is these levers which are operated successively by the control mechanism actuated by the operator as will appear.

Secured to each door portion 17 and to the shaft 15 is a rearwardly extending arm 25 adapted to swing in an arc underneath the door portion 13 as shown in Fig. 4 and to be engaged by a swinging gravity latch 26 arranged upon swinging latch shaft 27 extending through the end walls of the main chute body portion. There is, of course, a latch for each door at each vertical chute arrangement and each of the shafts 27, three in number, is provided with an operating lever 28 provided at its end with a pin 29. These pins 29 engage in slots 30 provided in a vertical flat slide bar 31 extending up along the outside of the end wall of the entire chute arrangement, as shown in Fig. 1. This bar is provided with an upper handle 32 handy for operation by the operator on the second floor and another lower handle 33 close to the treating machine for actuation by the operator at this point. The slots 30 provide for lost motion obviously necessary in avoiding the unlatching of a door which has been discharged and which should remain open to permit the passage of material past it from an upper hopper.

From the foregoing, it will be seen that the doors normally tend to close by their counterweights and tend to open when their loads are in place upon them and when open to the positions shown in dotted lines in Fig. 4 a straight chute is formed from the upper hopper straight through into the treating machine below. The tendency to open is, of course, overcome by the latches 23 which by reason of the weight of their actuating levers 24 assume latching position as shown so that once a door is closed by its counterweight it remains latched in this position until released.

The control mechanism for successively actuating the latches 23 comprises a vertical rod 34 swivelled for rotation in the end of an actuating lever 35 extending out to a point near the front of the treating machine. The connection between the bar and the lever is of a swivelled character so that the rod may turn freely for a purpose to be described. This rod is mounted in suitable bearings 36 and in bearings 37 in a cam block 37'. This cam block between its bearings is provided with vertical guides 38, Fig. 6, producing a track or groove 39 for pins 40 arranged in a collar 41 fast on the rod. These pins are 120° apart and are in the same transverse plane with respect to the axis of the rod. Secured to the cam block adjacent the left hand guide 38, as shown in Figs. 5 and 6, is a cam lug 42 provided with a leaf spring cam 43 extending in a spiral arrangement into the

groove 39. By this arrangement one of the pins 40 may be moved up through the groove 39 past the leaf spring cam and into the upper part of the groove and upon its return 5 downward movement it will engage upon the top of the cam spring and be ejected at the cam through an opening 44 through the guide 38. This operation turns the rod 34 to a position where the next pin 40 will be 10 moved into the path of a cam lug 45 on the opposite side of the rod and having its cam surface leading to a recess or opening 46 in the right hand guide 38. This recess 46 is closed by a lever spring 47 on the inner wall 15 of the right hand guide. As the rod descends the pin moves down the cam lug 45 through the recess 46 past the leaf spring 47 and into the guideway 49 ready to be elevated in a manner just described. This partial 20 rotation of this rod is through 120° and is utilized to bring latch engaging pins 48, three in number, arranged upon the rod at proper points into a position to successively operate the latch operating members 24. It 25 is obvious that these latch operating pins 48 are located at suitable points upon the rod with respect to the latch levers 24 which they are to operate.

In operation the work is classified into 30 lots, batches or loads, each in the proper amount on the second floor and charged into the three bins or hoppers formed above the doors in the main body of the chute. The doors, of course, are all latched in closed 35 position, an operation which is accomplished by the manipulation of the bar 31. The operator at the treating machine opens the outer and inner doors of the machine with a transverse row of pockets in alignment with 40 the chute portions 9. He then actuates the lever 35 which causes the first horizontal row of hoppers to discharge their loads into the pockets of the treating machine. The release of the lowermost latches 23 permits the 45 lowermost doors to move to open position due to the weight of material thereon. Such door opening movement causes the arms 25 of said doors to swing upwardly above the lowermost gravity latches 26, which latches 50 thereupon hold said lowermost doors in open position. The inner doors of these pockets are then closed and another row of pockets is brought around to position and opened. In 55 the discharge of the material from the first horizontal row of bins or hoppers, these doors are latched open and the next operation of the lever 35 through the mechanism described trips the latches of the second set of doors which discharge their predetermined 60 loads into the second set of pockets. This operation is repeated for the next set of pockets of the machine. To release the doors from the open position in which they are held by the gravity latches 26, the bar 31 is 65 raised, which causes said latches to swing

upwardly and thus move out of latching engagement beneath the door arms 25, whereupon said doors move to closed position under the influence of their counterweights 16, all as will be readily understood. 70

In the modification shown in Figs. 7 and 8, the main body portion of the feeding device is provided with rear inclined stationary floor portions 50 extending to a point above the door shafts 15 and the doors 17 extend from a point below the inner lower edges of these floor portions to the opening 19. Each door in this modification is provided with a pair of arms 51 at the ends and these arms are connected by a transverse strip 52 forming a counterweight for the door and normally tending to close it. These arms 51 extend horizontally when the door is closed and have a movement up under the floor portions 50. The latch mechanism for holding these doors open is the same as is used in the other form except that the bar 31 is provided with a slot 53 engaging a pin 54 projecting from the outside of the end wall. The upper end of this slot 53 engages at all times, when the bars are at rest, the pin 54 so that the weight of the bar 31 is not carried by the pins 29 and yet each latch pin 29 can assume the proper position in its slot 30 when the door is open. 90

What I claim is:

1. In load maintaining and feeding mechanism, a casing having an upper receiving and lower delivering opening, a plurality of hopper forming door portions arranged one above the other and mounted to swing between open and closed positions, means normally tending to move said doors to closed position, first mentioned latch means for holding said doors in closed position, second mentioned latch means for holding said doors in open position, operator operated means for releasing the second mentioned latch means to permit the doors to close, and operator operated control means for successively releasing the first mentioned latch means to produce successive discharges from the hoppers. 100

2. Load maintaining and feeding mechanism as in claim 1, wherein the operator operated means for releasing the second mentioned latch means operates all of such latches simultaneously. 110

3. Load maintaining and feeding mechanism as in claim 1, wherein the first mentioned latch means comprises an independent latch for each door, means normally tending to swing said latches into latching position, and operator operated means for successively releasing said latches. 120

4. Load maintaining and feeding mechanism as in claim 1, wherein the door portions are hinged intermediate the front and rear of the casing and wherein the forward parts 130

of said door portions swing downwardly for door opening movement.

5. Load maintaining and feeding mechanism as in claim 1, wherein the first mentioned latch means comprises a plurality of independent latches, one for each door, a weighted arm for each latch to move the same into door holding position, actuating means for said latches comprising a vertical shaft,
10 a plurality of release shoulders carried by said shaft and distributed symmetrically about the axis thereof, means for raising and lowering said shaft, and means engaging said shaft and causing it to rotate and
15 bring said latch releasing devices successively into engagement with their latches.

In testimony whereof I hereby affix my signature.

GEORGE B. WALLACE.
